(57) **CLAIM**

The ornamental design for an impeller for pump, as shown and described.

DESCRIPTION

FIG. 1 is a perspective view of an impeller for pump showing the new design;

FIG. 2 is another perspective view thereof;

FIG. 3 is a bottom plan view thereof;

FIG. 4 is front elevation view thereof;

FIG. 5 is a rear elevation view thereof;

FIG. 6 is a left side elevation view thereof; and,

FIG. 7 is a right side elevation view thereof.

The broken lines and unshaded surfaces bounded by broken lines form no part of the claimed design.
